ELECTRICAL CONNECTION MEANS

Charles S. Penfold, Bronson, Mich., assignor to
 H. A. Douglas Mfg. Co., Bronson, Mich., a corporation of Michigan

Application February 3, 1938, Serial No. 188,432

11 Claims. (Cl. 200—163)

This invention is directed to electrical switches and primarily to electrical connection means therefor.

Heretofore, electrical devices, particularly electrical switches, have been provided with electrical connections in the form of terminal posts or studs to which conductor wires are adapted to be either detachably or fixedly secured.

One object of the present invention is to provide terminals adjacent the ends of conductors and construct the switch in a manner whereby the terminals may be arranged to be directly engaged by the bridge member of the switch, and thereby eliminate the use and expense connected with manufacturing and assembling separate terminal posts on electrical switches and other devices.

Another object of the invention is to provide means whereby the terminals secured to the ends of the conductor wires may be detachably connected with respect to the switchback, the means here employed preferably consisting in the provision of a pin and slot connection between the terminals and the switchback, the slots preferably being provided in the switchback and the pins on the terminals.

Another object is to provide electrical connection means for a switch including in combination, an insulator and a plug conductor terminal, projection means provided on the terminal, means provided on the insulator adapted to cooperate with the projection means in a manner whereby said terminal may be detachably connected to said insulator, and means associated with the insulator for limiting the inward movement of the terminal when the terminal is being assembled with said actuator.

A further object is to provide a good mechanical connection between the terminals and the switchback, and primarily an arrangement whereby a particularly efficient direct electrical connection can be established between the bridge member of the switch and the terminals to control an electric circuit.

Referring to the drawing:

Figure 1 is a top plan view of an electric switch of the reciprocating type;

Figure 2 is a longitudinal section in elevation, taken substantially on line 2—2 of Figure 1, showing parts of the switch in detail, and including a pair of terminals;

Figure 3 is a section taken substantially on line 3—3 of Figure 1 showing a fragmentary part of the structure, including a terminal;

Figure 4 is a top plan view of a modified form of the invention;

Figure 5 is a longitudinal sectional view taken substantially on line 5—5 of Figure 4, showing more in detail the construction shown in Figure 4, and including a pair of terminals;

Figure 6 is a section taken substantially on line 6—6 of Figure 4, showing a fragmentary part of the structure, including a terminal; and

Figure 7 discloses another modified form of the invention.

Considering first the construction disclosed in Figures 1 through 3 of the drawing, numeral 1 represents a switch casing of any desirable shape and construction, and 2 is a switchback closing the open side of the casing, secured in place preferably by integral fingers formed on the casing which are clinched over and upon the switchback, as clearly shown. In fact the switchback may be termed an insulator or carrier.

A carrier 4 of insulating material carrying a bridge member 5 is preferably supported upon resilient means in the form of an elongated leaf spring 6 secured to the carrier, and said spring is adapted to slidably engage the bottom wall of the casing. A handle 7 is suitably connected to the carrier so that the bridge member may be moved from the inoperative position shown into effective electrical engagement with the inner convex extremities of the plug conductor terminals 8 and 9 to close an electric circuit. It is to be understood that the switch shown is merely illustrative, and that if desired may be of a rotary, toggle, or other type. Also, that insofar as this modification is concerned, it is immaterial whether the spring means urging the bridge member in a direction to engage the terminals is arranged as shown, or is located between the carrier and a bridge member of a switch, or whether the bridge member itself is of a resilient character, in which event, the use of separate resilient means may be entirely eliminated. These variations are all well known in the art.

The switchback 2 may be comprised of a plurality of superimposed members, but as here shown, is preferably a single block of suitable insulating material. A pair of spaced apart apertures 10, of like size and shape, are provided in the switchback and extend entirely transversely therethrough. Each aperture preferably consists of a round hole having two slots or guideways 11 diametrically arranged which intersect the margin of the hole. Adjacent the lower extremity of each aperture there is provided in the switchback, notches or seats 12 which

intersect the margin of the hole, and there are diametrically arranged preferably at right angles to the slots or guideways 11.

The terminals 8 and 9 may be united to the conductor wires 13 by any suitable means or method, such as by swaging, as clearly indicated, and each terminal is preferably provided with two outwardly extending projections 14 which in the present instance are in the form of cylindrical pins, arranged diametrically opposite to each other. These projections may be formed integrally on the terminals, or may be separate parts secured to the terminals in any suitable manner.

From the foregoing description, it will be clearly evident that to connect a terminal to the switchback, it is merely necessary to insert a terminal into an aperture 10 with the projections 14 extending into the slots or guideways 11, and press it inwardly against the resistance exerted by the spring 6 a distance whereby the projections clear the lower extremities of the slots 11, whereupon the terminal is rotated either to the left or right until the projections catch and snap into the notches or seats 12 when the terminals are released. These seats are preferably of a depth whereby to entirely receive the projections 14, as clearly illustrated.

The arrangement is of such a character that the terminals are firmly but detachably secured in place, and it is to be understood that each terminal may be provided with but one projection, and the switchback with but one slot and notch if found desirable, also, that any form of projection means or receiving means for the projection means may be provided.

Referring now to the modified form of the invention disclosed in Figures 4 through 6, the object is to provide means whereby to assist in locating the projections on the terminals so that the terminals may be more easily and quickly assembled with respect to the switchback. In this modification, all of the switch elements, except the terminals and the switchback, are of the same construction, as above described.

The switchback, as here shown, is preferably comprised of a plurality of members 50 and 51 of insulating material. The outer member 50, is desirably moulded and made somewhat thicker than the inner member 51 which is preferably made of sheet material. The outer member is provided with a pair of spaced apart apertures 52 and guideways or slots 53 corresponding to the apertures 10 and slots 11 above referred to. Each of these apertures 52 is also provided with a bayonet notch, consisting of a seat 54, projection 55, and an entrance slot 56, arranged in conjunction with each of the guideways or slots 53 as clearly shown in Figure 6, and preferably circumferentially and diametrically opposite to each other, as shown in Figure 4. The inner member 51 is provided with a pair of spaced apart apertures 57 which are in line with the apertures 52 and of the same diameter. This member acts as a stop which the projections engage to limit inward movement of a terminal and locates the projections in a position to be received by the bayonet notches.

As clearly shown in Figures 5 and 6, the projections provided on each terminal are set back from the end thereof a distance slightly greater than the projections 14 described above in order that the projections will properly cooperate with the bayonet notches provided in the outer member 50.

The parts are so constructed and arranged that each terminal may be more easily and quickly assembled with the switchback, and assembly may be accomplished by merely inserting the end of the terminal and the projections into the apertures 52 and guideways or slots 53, respectively, and pressing the terminal inwardly against the resistance exerted by the resilient means or spring until the projections engage the member 51 which renders further inward movement of the terminal impossible, and the terminal is then rotated in a clockwise direction, the projections passing through the entrance slots 56 and into engagement with the abutments 58, whereupon the terminal is released, and the resilient means function to urge the projections into the bayonet seats 54. Thus, improved means are provided whereby to detachably connect terminals to a switchback. Obviously, it is to be understood that the various slots and notches may assume different shapes and arrangements, and that it is immaterial whether a clockwise or counter-clockwise movement is required to seat the projections of the terminals, including the degrees of rotation.

Referring to the modified construction disclosed in Figure 7, there is provided an arrangement in which the terminals are provided with spring pressed contact means adapted to engage the bridge member, said means taking the place of separate resilient means corresponding to the spring 6 or other arrangement.

In this modification, the switchback may be constructed according to either of the modifications shown and described above, or otherwise, but since the terminals are quite long it is desirable that the switchback be rather thick, and therefore a switchback of the character last described is preferably used.

The terminal here shown preferably includes a body 60, having a tubular part 61 in which is slidably secured a contact 62 pressed outwardly by a helical spring 63. The terminal is also preferably provided with a pair of pins 64 corresponding to the pins above described which cooperate with the bayonet notches in the switchback 65 to detachably yet firmly secure the terminal thereto. Obviously the contact is adapted to engage the bridge member 66. Since the resilient means is operatively related to the terminals the use of a spring such as 6 may be eliminated, in which event the carrier directly engages the bottom wall of the casing as shown.

Having thus described my invention, it is obvious that various immaterial modifications may be made in the same without departing from the spirit of the invention; and, therefore, I do not wish to be understood as limiting myself to the exact forms, constructions, arrangements, and combination of parts, herein shown and described.

I claim:

1. Electrical connection means for a switch including in combination, an insulator and a rigid plug conductor terminal, an aperture extending through said insulator, cooperating means provided on said insulator, projection means provided on said terminal adapted to connect with said cooperating means when said terminal is rotatably arranged in said aperture, and separate insulating means engaging said insulator spaced from said cooperating means and engageable with said projection means for predetermined the location of said projection means with respect to

said cooperating means when the terminal is being assembled with said insulator.

2. An electric switch including in combination, a casing, an insulator adapted to receive a terminal secured to said casing, a terminal receiving aperture including a notch provided in said insulator, a rigid terminal extending entirely through said aperture and provided with projection means cooperating with said notch, bridge means arranged in said casing adapted to be brought into electrical engagement with said terminal, and resilient means associated with said bridge means functioning to hold said projection means in said notch.

3. An electric switch including in combination, a casing, an insulator adapted to receive a terminal secured to said casing, a terminal receiving aperture including a notch provided in said insulator, a terminal extending into said aperture and provided with projection means adapted to cooperate with said notch, means associated with said insulator for predetermining the location of said projection means with respect to said notch when said terminal is being assembled with said insulator, bridge means arranged in said casing adapted to be moved into electrical engagement with said terminal, and resilient means associated with said bridge means for holding said projection means in said notch.

4. An electric switch including in combination, a casing, an insulator adapted to receive a terminal secured to said casing, a terminal receiving aperture including cooperating means provided on said insulator, a terminal extending into said aperture and provided with projection means adapted to connect with said cooperating means, bridge means arranged in said casing adapted to be moved into electrical engagement with said terminal, and resilient means associated with said bridge means functioning to hold said projection means in connection with said cooperating means.

5. A claim as set forth in claim 4, including a sheet of insulating material associated with said insulator and provided with a terminal receiving aperture in line with the aperture provided in said insulator, said sheet providing a stop which said projection means engage to limit inward movement of the terminal during assembly with the actuator to predetermine the location of said projection means with respect to said cooperating means in a manner whereby said projection means is placed in a desirable position to be received by said cooperating means.

6. Electrical connection means for a switch including in combination, an insulator and a plug conductor terminal, an aperture extending through said insulator and cooperating means provided on said insulator, projection means provided on said terminal adapted to connect with said cooperating means when said terminal is arranged in said aperture, a spring pressed contact carried by said terminal, and means engaging said insulator for predetermining the location of said projection means with respect to said cooperating means when the terminal is being assembled with said insulator, and bridge means adapted to be moved into electrical engagement with said spring pressed contact, the spring associated with said contact functioning to hold said terminal in connection with said cooperating means.

7. An electrical switch including in combina-

tion, a casing, an insulator secured to said casing, a terminal receiving aperture including a notch provided in said insulator, a plug terminal permanently connected to a conductor extending into said aperture, that portion of the terminal extending into said aperture being of a diameter less than the diameter of said aperture, said terminal having projection means adapted to cooperate with said notch whereby said terminal may be detachably connected to said insulator while said insulator is secured to said casing, bridge means arranged in said casing adapted to be brought into electrical engagement with said terminal and separate resilient means holding said projection means in said notch.

8. Electrical connection means for a switch including in combination, an insulator provided with an aperture, a rigid plug conductor terminal having a portion extending into said aperture, projection means provided on said terminal, means provided on said insulator adapted to cooperate with said projection means in a manner whereby said terminal may be attached to said insulator, and means engaging said insulator and spaced from said cooperating means on said insulator and engageable with said projection means for limiting the inward movement of said terminal when the terminal is being assembled with said insulator.

9. Electrical connection means for an electric switch provided with an insulator, said insulator provided with a terminal receiving aperture and a notch, a rigid terminal extending into said aperture and provided with means projecting into said notch, and separate insulating means engaging the under surface of said insulator providing a stop adapted to be engaged by said projecting means to predetermine the position of the terminal when the latter is being assembled with said insulator.

10. An electric switch including in combination, a casing, an insulator adapted to rotatably receive a plug conductor terminal secured to said casing, a terminal receiving aperture including cooperating means provided on said insulator, a plug conductor terminal extending into said aperture and provided with projecting means adapted to connect with said cooperating means, a spring pressed contact carried by said terminal, and bridge means arranged in said casing adapted to be moved into electrical engagement with said contact, the spring associated with said contact acting to press said projecting means into engagement with said cooperating means whereby to prevent rotation of said terminal with respect to said aperture.

11. An electric switch including in combination, a casing, an insulator adapted to receive a terminal secured to said casing, a terminal receiving aperture including cooperating means provided on said insulator, a terminal extending into said aperture and provided with abutment means adapted to connect with said cooperating means, bridge means arranged in said casing adapted to be moved into electrical engagement with said terminal, and resilient means associated with said bridge means functioning to hold said abutment means on said terminal in connection with said cooperating means.
